WINDOW SASH GUIDE

Arthur M. Starck, Goode, Va., and William R. Starck,
Greenwich, Conn., assignors to A.M.S. Corporation,
South Norwalk, Conn.

Filed Jan. 15, 1973, Ser. No. 323,645

Term of patent 14 years

Int. Cl. D25—01

U.S. Cl. D13—6

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a front perspective view of a portion of a window sash guide for double hung windows embodying our new design.

FIG. 2 is a fragmentary front elevation view of a portion of the structure of FIG. 1.

FIG. 3 is a bottom plan view of the structure of FIG. 1.

FIG. 4 is a fragmentary rear elevation view of a portion of the structure of FIG. 1.

FIG. 5 is a fragmentary left side elevation view of the side of the structure shown in the previous figures.

FIG. 6 is a fragmentary opposite right side elevation view of the same structure.

FIG. 7 is a fragmentary front perspective view of a portion of another window sash guide for double hung windows embodying a variation of our new design.

FIG. 8 is a fragmentary front elevation view of a portion of the structure of FIG. 7.

FIG. 9 is a bottom plan view of the structure of FIG. 7.

FIG. 10 is a fragmentary rear elevation view of a portion of the structure of FIG. 7.

FIG. 11 is a fragmentary left side elevation view of the side of the structure shown in previous FIGS. 7-10, and

FIG. 12 is a fragmentary opposite right side elevation view of the same structure.

We claim:

The ornamental design for a window sash guide, substantially as shown.
